UNITED STATES PATENT OFFICE.

HENRI ADOLPHE DEROUY, OF PARIS, FRANCE.

APPARATUS FOR PRODUCING ACETYLENE GAS.

SPECIFICATION forming part of Letters Patent No. 604,025, dated May 17, 1898.

Application filed July 2, 1896. Serial No. 597,846. (No model.) Patented in France April 4, 1896, No. 255,338; in Luxembourg May 7, 1896, No. 2,535; in Belgium June 6, 1896, No. 121,769; in England June 9, 1896, No. 12,683; in Italy June 9, 1896, No. 41,752/51, and in Tunis June 11, 1896, No. 183.

To all whom it may concern:

Be it known that I, HENRI ADOLPHE DEROUY, a citizen of the French Republic, residing at Paris, France, have invented certain new and useful Improvements in Apparatus for the Production of Acetylene Gas, (for which Letters Patent have been obtained in France, No. 255,338, dated April 4, 1896; in Italy, No. 41,752/51, dated June 9, 1896; in Belgium, No. 121,769, dated June 6, 1896; in Tunis, No. 183, dated June 11, 1896; in Luxembourg, No. 2,535, dated May 7, 1896, and in Great Britain, No. 12,683, dated June 9, 1896,) of which the following is a full, clear, and exact description.

My invention has relation to apparatus for the production of acetylene gas from calcium carbide; and it has for its object, among others, to provide a simple, inexpensive, and efficient apparatus whereby acetylene gas may be produced in an economical and uniform manner; and the invention consists in the novel construction, arrangement, and combination of parts, as hereinafter fully described, illustrated in the drawings, and pointed out in the appended claims.

In the drawings, Figure 1 is an elevation of one form of my improved apparatus. Fig. 2 is an elevation, partly in section, of a slightly-modified form of the apparatus. Fig. 2^a is a vertical sectional and a plan view of a receptacle or basket for the calcium carbide. Fig. 3 is a vertical section and a plan view of another form of apparatus.

My invention embodies, preferably, at least two receptacles or generators for the reception of the calcium carbide and the generation of the gas, so that when the charge in one has been exhausted the same may be isolated or cut off from the remainder of the apparatus and the charge in the other receiver operated upon while the first receiver is being recharged. I thus obtain an economical and rapid working of the apparatus.

Referring particularly to Fig. 1, A and B indicate the two generators, into each of which a charge of carbide of calcium may be placed and closed by covers 3^x. 1 indicates a water-supply pipe having branches 2 and 3, leading, respectively, into the receivers, prefer-

ably at the bottom, and 7 indicates a valve or cock located at the junction of the branches and adapted to cut off the water-supply to either or both of the receivers at will. A gas-outlet pipe 9 communicates by branches 55 10 and 11 with the generators, preferably at the top, and a valve or cock 8 is adapted to close communication between either or both of the generators and the said pipe 9. 12 indicates a pipe which leads from the upper 60 part of generator A to the bottom of generator B, while 13 indicates a similar pipe leading from the upper part of generator B to the bottom of generator A. The pipes 12 and 13 join each other at the point of crossing, and 65 a valve 10', located at the junction, is adapted to close the passage of either the pipe 12 or the pipe 13.

With the described form of apparatus the valve or cock 7 is turned to open communication between the water-supply and receiver A, valve 8 is turned to open communication between said generator and pipe 9, while cock 10' is turned to open the passage of pipe 12. Water now being admitted into the generator 70 A, gas will be evolved and pass out through the pipe 9 to a purifier, gasometer, or other receptacle. When the calcium carbide is exhausted in generator A and the water reaches a level with the mouth of pipe 12, the excess 75 will flow through said pipe into the generator B and, acting upon the calcium carbide therein, produce gas. If, however, it is desired to discharge the surplus water in generator A and charge it again with fresh calcium carbide 80 while receiver B is operating, the generator A is cut off from the remaining part of the apparatus by turning cocks 7 8 10' so that water will flow from pipe 1 directly into generator B, the passage of pipe 12 will be closed 85 and pipe 13 opened, and communication between generator B and pipe 9 will be effected. While the gas is being evolved in generator B generator A may be discharged and recharged with calcium carbide, so that by the 90 time the calcium carbide in generator B is exhausted the generator A will be ready to again operate, and as soon as the calcium carbide in generator B is exhausted the excess of water will flow through pipe 13 into generator A, 95 100

and said generator B is then cut off by properly manipulating the cocks and then recharged similarly to generator A. In this manner I obtain an economical and rapid 5 working of the apparatus and a steady production of gas, and said production may be regulated for any desired number of hours or days by properly manipulating the cocks so as to increase or decrease the production 10 of gas within a given time.

The calcium carbide may be placed within independent receptacles which are removably introduced into the generators, so that they may be readily removed for the purpose of 15 being recharged with fresh calcium carbide.

In Fig. 2 I show a construction of receptacle which I preferably use, although I might use plain receptacles, such as indicated in dotted lines in Fig. 1, the same being perforated either upon their entire surfaces or only 20 at bottom for the passage of the water thereinto to act upon the calcium carbide. The form shown in Fig. 2^a comprises a casing or vessel 15, having a bail or handle 15^x and divided into several compartments (the number of which may be varied) by vertical partitions 16, and in each of these compartments is placed a perforated basket or receptacle 17, each of which latter is divided by a partition 25 18 into two divisions, in which latter the calcium carbide is placed. I preferably pack the calcium carbide in the receptacles 17 in layers separated by layers of some inactive material, as gravel or the like, and in Fig. 2^a the section 30 and curved dotted lines represent the layers of active material or calcium carbide and the intervening spaces the inactive material. b is an overflow for the casing. By thus separating the active material or calcium carbide 35 into small sections or layers the production of gas is rendered more regular and uniform and the calcium carbide is more evenly and thoroughly acted upon by the water.

In Fig. 2 the general arrangement and operation of the apparatus is the same as that described with reference to Fig. 1, the arrangement of the connecting pipes and cocks being only slightly modified. A' and B' indicate the generators; 1', a water-supply pipe 45 connecting by branches 2' 3' with the generators; 2^a, a cock located at the junction of the branches and adapted to place the water-supply pipe in communication with either of the generators. 4' is a gas-outlet pipe which 50 communicates by branches 5' 6' with the generators and also communicates with a purifier 7', containing any suitable purifying material, as coke, which purifies and dries the gas. The purifier might be replaced by any 55 suitable condensing device whereby the water carried along by the gas is condensed. 8' indicates a cock located at the junction of the gas-outlet pipe and its branches and controlling the communication between the generators and the said outlet-pipe. 9' indicates a pipe which places the generators directly 60 into communication with each other, and 9^a

a cock therein to control such communication. 10^a indicates a vessel charged with the supply-water. 13^a is a water-gage, and 11' 70 are safety-pipes which communicate with the branches 5' 6' and lead down into the water-reservoir 10', into the water therein, the lower end of said pipes being constantly submerged. Each of the generators is provided with a gas-tight cover 13', which is provided interiorly 75 with a circumferential gutter 14' to collect the water of condensation. Each generator contains the ordinary receptacle or preferably the form of receptacle described just above 80 and shown in Fig. 2^a. I would state that the several divisions or compartments of the basket are in practice made to communicate with each other by any suitable means, preferably by means of apertures located toward 85 the upper end of each of the partitions, as at points a. In operation the valve or cock 8' is turned to establish communication between the generators and the purifier, and cock 9^a is turned to establish direct communication 90 between said generators. Then the cock 2^a is turned to establish communication between the generator A' and the water-reservoir. The water flows now into a cup, as 20', provided in one of the compartments of the receptacle 15, whence it falls to the bottom, and, passing through the perforations in the basket 17, comes into contact with the calcium carbide therein, and gas is evolved and passes out through the pipe 4' to the purifier. 95 As the water rises in the described basket 17 it overflows through the aperture into the adjoining basket 17 to attack the calcium carbide therein, and from the latter basket the overflow flows to the next adjoining basket, and so on till all the calcium carbide contained in the several baskets is exhausted. The water then flows from the generator A' by pipe 9' into generator B', similarly provided with baskets of calcium carbide, 100 where the operation is repeated. While gas is being evolved in generator B', the generator A' may be recharged after turning cock 8' to cut off said generator A' from the gas-outlet pipe and turning cock 9^a to cut off 105 direct communication between the generators and also turning cock 2^a to allow water to flow only into generator B'. The cover of generator A' is now taken off and the several baskets 17 removed and the surplus water 110 run off through waste-pipe 21'. The baskets having been recharged are again placed within the generator A' and the cover replaced and cocks 9^a and 8' turned to establish communication between the generators 115 and the generator A' and the purifier; but the water-regulating cock 2^a is not turned until generator B' is to be refilled, when it cuts off the water-supply to the latter and establishes it for generator A'. Any gas which 120 may have escaped into the reservoir through the safety-pipes is conducted away through a pipe 20. The water-supply pipe may be made of glass, so that the action of the water 125

may be observed. It will be observed that the pressure of the gas being generated within the generators will regulate the admission of water, a greater pressure of gas tending to diminish the supply of water, and vice versa, and in this manner the calcium carbid will be moistened in an automatic manner and just to the desired extent.

In Fig. 3 I show another form of apparatus wherein 21, 22, and 23 indicate generators, and at the bottom and centrally is arranged a specially-constructed cock 35, having water-passage 24 and gas-passage 25. At the top of the apparatus is arranged a specially-constructed cock 36, having gas-outlet passage 27, communicating with a pipe 28. The cocks are so constructed that the casings thereof can turn simultaneously with the generators, which are in this construction adapted to be rotated, while the plugs of said cocks remain stationary. A cover 29 is arranged over a charging and discharging opening in each of the generators. The water passing through passage 24 enters the generator 21, and, coming in contact with the calcium carbid contained therein within suitable removable baskets, as before described, gas is evolved and passes through a pipe 30 in said generator and out through passage 25 into the generator 22, and thence out through passage 27 and pipe 28. When the water fills the generator 21 and the calcium carbid is exhausted, the water takes the same course as the gas and enters the generator 22. I then give one-third of a revolution to the apparatus, whereby the communication between generators 21 and 22 is closed and that between generator 22 and generator 23 opened to permit the water to act upon the calcium carbid in the said generator 22 in the same way that it did as to generator 21, and in the same way acts upon the calcium carbid in generator 23 when the calcium carbid in generator 22 is exhausted. This is repeated again and again, a third of a turn being given to the apparatus each time that a generator becomes exhausted. The apparatus, instead of being composed of one large cylinder, as shown, divided into three compartments to form three generators, may be composed of independent cylinders, each constituting a generator, and the number of generators may be varied, and it will be un-

derstood that the passages in the cocks will be varied correspondingly. This form of apparatus (that shown in Fig. 3) is very simple and easily manipulated and avoids the necessity of manipulating cocks or valves.

What I claim, and desire to secure by Letters Patent, is—

1. In an apparatus for the production of acetylene gas, the combination of two generators, a basket or receptacle removably arranged in each of said generators and divided into compartments in communication with each other, a vessel in each of the latter adapted to receive calcium carbid, a water-pipe in communication with a compartment of each generator, a cock or valve adapted to regulate the supply of water to either of the compartments, a gas-outlet pipe in communication with the generators, a cock or valve adapted to control the communication of the gas-outlet pipe with either of the generators, an overflow water-pipe connecting the generators together and adapted to conduct the overflow from one generator into the other, and a valve or cock arranged in said overflow-pipe.

2. In an apparatus for the production of acetylene gas, the combination of generators, a water-pipe in communication with the generators, a cock or valve adapted to regulate the supply of water to either of the generators, a gas-outlet pipe in communication with the generators, a cock or valve adapted to control the communication of the gas-outlet pipe with either of the generators, an overflow water-pipe connecting the generators together and adapted to conduct the overflow from one generator into the other, a valve or cock arranged in said overflow-pipe, a water-reservoir with which the water-supply pipe is in communication, and pipes in communication with the gas-outlet pipe and leading into the reservoir, and adapted to have the opposite end submerged in the water contained in the reservoir.

In testimony that I claim the foregoing I have hereunto set my hand this 3d day of June, 1896.

HENRI ADOLPHE DEROUY.
